NAIL CLEANING APPARATUS

William Thompson, Cleveland Heights, Ohio, assignor to The American Steel and Wire Company of New Jersey, a corporation of New Jersey

Application June 27, 1942, Serial No. 448,877

4 Claims. (Cl. 51—164)

The present invention relates to apparatus peculiarly well suited for cleaning nails directly after they come from a nail making machine, and for receiving the same and delivering them substantially continuously in sequential batches.

The improved apparatus employs a revoluble cleaning cylinder adapted to intermittently receive various loads of nails. This cylinder carries a charge of sawdust which is effective to collect grease, foreign matter and metallic whiskers frequently present on nails coming from a modern nail making machine. The cleaning cylinder is equipped with one or more spiral fins adapted to carry the nails forward to the exit end of the cylinder which, because of the rotation, will move the nails upward partly by the force exerted by the gravity of the nails sliding along the spiral fins as the cylinder rotates. The action is such that the nails cascade over one another and intermix with the sawdust or other cleaning agent. A scrubbing or scouring action takes place, and this action is augmented by the tendency of the nails in the upper part of the revolving cylinder to travel backward toward the entrance end thereof, this action being secured in part by the conjoint action of the conical outlet head of the cylinder in combination with certain scoops, hereinafter referred to in detail, and the spiral fins secured to the interior of the cylinder.

At its exit end the cleaning cylinder is equipped with an improved type of closure and with special operating means whereby the closure can be opened by a power operated member during the rotation of the cylinder. From the cleaning cylinder the nails, together with the sawdust or other scouring agent, are discharged into a second revolubly mounted drum, herein referred to as the screening drum. This screening drum is so constructed and arranged that it will separate out the cleaning agent and the extraneous matter, such as the metallic whiskers, and direct such cleansing agent and extraneous matter to respective discharge points and the cleansed nails to a vibrating chute adapted to guide them to kegs or storage receptacles carried by a known form of shaking table.

For a more complete disclosure of the invention, reference should be made to the following specification, the accompanying drawings and the appended claims.

In the drawings:

Figure 1 is a view partly in elevation and partly in section showing the essential elements of a nail cleaning apparatus embodying the invention;

Figure 2 is an enlarged longitudinal section

through the cleaning cylinder constituting an important element of the present invention;

Figure 3 is a section on line III—III of Figure 2;

Figure 4 is a section on line IV—IV of Figure 2;

Figure 5 is a detail longitudinal section through the screening drum constituting another of the essential coacting elements of the present invention;

Figure 6 is a section on line VI—VI of Figure 5;

Figure 7 is a section on line VII—VII of Figure 5;

Figure 8 is an enlarged detail section illustrating one end of the screening drum and an adjacent portion of a chute adapted to receive and carry away the sawdust or cleansing agent ejected by the screening drum;

Figure 9 is an enlarged detail of a perforated section of the screening drum; and

Figure 10 is a view of the cover plate for the perforated section of Figure 9.

Referring in detail to the drawings, in the normal use of the device of the present invention a given batch of nails, for example, say about 1500 pounds, are loaded into a portable container such as indicated at 1 in Figure 1 and transported by any suitable means to the nail cleaning apparatus and placed on racks 2 which are pivotally mounted at 2^a on a platform elevator 3. The proper amount of sawdust required to clean the nails is placed on top of the nails contained in each container. After two containers of nails have been placed on the individual racks on the elevator platform, the latter is raised to the proper level, whereupon the containers are tilted about their pivotal supports 2^a until they rest upon a roller 4 which travels vertically in guides 5. The movement of this roller is effected by a hoist suspended from an overhead structure support 6. The hoisting ropes are trained over upper sheaves 7 and lower sheaves 7^a and both ends of the rope are attached to a vertically slid able block to which the roller is pivoted.

As thus arranged, as the hoist ropes are lowered, the roller 4 will also descend. When the operator lowers the hoist ropes causing the roller 4 to descend, the nails and the sawdust which were placed thereon will be dumped upon a vibrating member 8 adapted to feed the nails and sawdust at a substantially constant rate into a chute 9 which in turn directs the same into the opening shown at the left end of the cleaning cylinder 10 in Figure 2. A motor 11 transmits rotary motion to the cleaning cylinder by means of a sheave 12 and V-belts 13 trained over a

grooved pulley 14 carried by a jack shaft 15 mounted in suitable bearings. The shaft carries a drive pinion 16 which meshes with a gear 17 secured to the exterior of an annular end member 17a. The cleaning cylinder 10 is equipped with annular tires 18 which serve to revolvably mount the cylinder on a plurality of supporting rollers 19 mounted in suitable bearings. Located within the cylinder and secured to the inner substantially cylindrical shell plates thereof there is provided a pair of substantially helical fins 20 formed of stock rolled steel bars about $\frac{1}{2}$ inch thick by 4 inches wide. The two helical fins shown are preferably located diametrically opposite one another and each extends around approximately one-fourth of the inner circumference of the cylinder while at the same time progressing longitudinally along approximately a true helical line.

In practice the speed of the motor and the proportion of the drive sheaves and pulleys shown are such that the cleaning cylinder is rotated at about 28 R. P. M. Thus as the cylinder revolves, the helical spiral fins 20 repeatedly pick up the mixture of nails and sawdust or other cleaning agent and drop them. This repeated picking up and dropping of the mixture of nails and sawdust exerts a scrubbing or cleansing action which is effective to remove any slight metallic burr or whiskers on the nails and to thoroughly mix the sawdust with the nails. Thus this sawdust or other cleansing agent absorbs oil, grease or other foreign matter carried over on the surface of the nails from the nail making machine.

In practice the nails are tumbled in the cleaning cylinder 10 for approximately 20 minutes, whereupon the cover 21 at the discharge end of the cleaning cylinder is opened. This cover is secured to and slidably supported by a shaft 22 which carries a collar 23 which is normally yieldingly pressed by springs 24 in a direction tending to hold the cover closed. At the extremity of the shaft 22 remote from the cover 21 there is secured a disk 25. A yoke 26 secured to a rock shaft 27 carries rollers 28 which when the yoke is rocked counterclockwise, tends to retract the cover to open position. For rocking the yoke the shaft 27 is provided with an operating arm 29 pivotally connected at 30 to a vertically movable member 31 arranged to be actuated by a suitable power device, such as the electrically operated thruster 32 which is pivotally mounted at 33 to a bracket 34 secured to any fixed frame member.

At the discharge end of the cleaning cylinder a plurality of scoops 35 are provided. These, as shown in Figures 2 and 3, are so arranged that they receive the nails sliding along the helical fins 20. These scoops are of trough-like construction, being provided with guide flanges 36 which are disposed at substantially 90 degrees to the nail carrying surface thereof. As thus arranged, upon rotation of the drum the nails will slide down the fins into the scoops whereupon continued rotary motion will dump the nails and cleansing agent, such as sawdust mixed therewith, onto the inclined or frusto-conical surface 37 of the end closure head 38. Thus the combined action of gravity and the rotary motion of the cylinder will force the nails to crowd over one another and cause certain of them to travel countercurrent with the direction of travel of that part of the batch sliding over the fins. Thus there is a peculiar cooperative relationship between the helical fins, the inclined scoops and the oppositely inclined frusto-conical surface of the

end head 38. After each given batch of nails has been subjected to this cleansing action, the circuit controlling the operation of the thruster 32 will be closed by a simple push button controller, whereupon the shaft 27 will be rocked so as to cause the yoke 26 to transmit a sliding motion to the rod 22 against the yielding force of the springs 24. Thus the cover 21 will be moved to open position, whereupon the mixture of cleansed nails and the cleansing agent, such as sawdust or the like, will be discharged through the outlet orifice 39 formed in the casing member 40 secured to the outlet extremity of the cleaning cylinder. Thus the mixture of nails, sawdust, whiskers and removed foreign matter will be discharged to a chute 41 which in turn will empty the mixture of nails, etc., into a screening drum 42 shown in detail in Figure 5.

This screening drum in many respects is quite similar to the cleaning cylinder, being provided with tires 43-43 which ride on rollers 44 so as to rotatably support the structure. The screening drum carries a ring gear 45 meshing with a pinion 46 keyed to a shaft 47 mounted in suitable bearings 48 and carrying a grooved pulley 49 driven by a belt 50 from a grooved pulley 51 carried by the armature shaft 52 of a motor 53 whose circuit is adapted to be controlled by a conventional form of push button controller.

To the inner surface of the screening drum there is secured a pair of diametrically opposed helical fins 54-54, each of which makes approximately one-fourth of a turn while progressing longitudinally of the cylinder. At their extremities the fins are adapted to coact with scoops 55-55. The cleaning cylinder carries a substantially frusto-conical end head 56, whose outlet orifice 58 is normally blocked by a closure member 59 carried by a slidably mounted rod 60 which carries a collar 61 urged to the left in Figure 5 by compression springs 62. The rod 60 at one end carries a disk 63 for coaction with a yoke 64 secured to a rock shaft 65 carrying an arm 66 pivotally connected at 67 to a member 68 adapted to be actuated by an electrically operated thruster 69 which is pivotally supported at 70 to a suitable fixed support 71. The circuit of the thruster is adapted to be opened and closed by a conventional form of push button controller. Thus the operating mechanism for the closure 59 which controls the discharge of nails from the screening drum 42 is practically identical with the mechanism controlling the operation of the cover for the cleaning cylinder previously described.

The chief difference between the cleaning cylinder and the screening drum is that the latter has a plurality of perforated sections. In the embodiment of the invention illustrated, four such sections are illustrated, the same being spaced 90 degrees apart. These perforated sections are each indicated generally by reference numeral 72, there being a multiplicity of perforations 73 formed in each of the sections. Secured to the exterior of the cleaning cylinder in juxtaposition to each of the perforated sections there is a cover plate 74 maintained in any desired or predetermined spaced relation to the exterior of the perforated section by spacer members 75. The spacer members illustrated, as best shown in detail in Figure 9, constitute the heads of bolts 76, whose threaded shanks are screwed into the cylindrical wall of the screening drum. The cover plates 74 are flanged outwardly at 77 and are provided with bracket members 78 slotted for co-

action with bolts 80 which pass through the slots and which are threaded into the shell of the screening drum so as to thus hold the cover plates firmly in engagement with the spacer members 75.

In normal operation the screening drum makes approximately 28 R. P. M. The combined action of rotation of the drum and the forward feed imparted by the fins 54 agitates the mixture of cleansed nails and sawdust or other cleaning agent. Thus as the screening drum revolves, the agitation or tumbling action eventually segregates all of the sawdust or other cleansing agent, metallic whiskers and other extraneous matter on the inside surface of the drum. Thus as the same rotates, the extraneous matter passes through the various perforated sections of the screening drum and collects in the space between the cover plates and the exterior of the drum. In short, the thoroughly cleansed nails are effectively separated from the cleansing agent and extraneous foreign matter. The sawdust or other cleansing agent and extraneous matter thus collected on the inner surface of the cover plates 74 slide therealong due to the rotary motion, and when such separated material reaches the edges 81 of the cover plate, it falls by gravity into the hopper-like bottom 82 of a casing 83 which encloses the screening drum. As the metallic whiskers fall out of the screening drum, they gravitate to the bottom of the hopper and eventually fall through a slot 84 and pass to a suitable container located below the hopper bottom. The sawdust is removed through an opening 85 and withdrawn through suitable conduit by means of a motor driven exhauster which carries it to a storage bin, not shown. There is a hood 86 located over the discharge end of the cleaning cylinder 10 and a similar hood 87 located over the discharging end of the screening drum so as to catch any sawdust which might escape from the drum while the nails are being discharged, these hoods 86 and 87 being connected by pipes, not shown, to a suitable motor driven exhauster, not shown, which also connects with the casing 83.

After an interval of about 10 minutes from the time a given batch of about 1500 pounds of nails is delivered to the screening drum, the closure 59 will be opened, whereupon the nails will be discharged to an inclined chute 88 which is vibrated in a known manner. This chute will deliver the nails to a plurality of kegs 89 or other shipping containers mounted on a shaking device 90 of known construction operated by a pitman 91 driven by an eccentric 92 carried by shaft 93 carrying a pulley 94 which is driven by a belt 95 from a motor 96. After the kegs or other receptacles have been filled to desired capacity, they will be transferred to a shipping point on a suitable car 97.

From the foregoing it will be apparent that the described apparatus is effective to periodically receive large batches of nails which are cleaned in the continuously rotating cleaning cylinder, in which they are agitated and freed from grease and metallic whiskers or burrs resulting from a normal nail making operation. While the cleaning cylinder continues to revolve, the cleansed nails are periodically transferred to the screening drum wherein the cleansing agent is separated out and thus the final product will be in condition, having been thoroughly cleansed and ready for shipment. Any given batch of nails may be subjected to screening for a suitable time 75

interval which is dependent largely upon the size of the nails. It will be understood that for different sizes of nails, holes of different sizes may be used in the perforated sections. Also the distance 5 between the cover plates and the exterior of the screening drum may be varied by inserting spacer elements of different thicknesses to suit the particular product being handled.

While I have described quite precisely the 10 construction and arrangement of an apparatus which an actual reduction to practice has shown to be very efficient, it is not to be construed that I am limited thereto since various modifications and substitutions of equivalents may be made by 15 those skilled in the art without departure from the underlying features of the invention as defined with particularity in the appended claims.

I claim:

1. Apparatus for cleaning nails comprising a 20 rotary cleaning cylinder having helical fins therein, means for feeding a batch of nails and a cleansing agent into said cylinder, flanged scoops located in the cylinder in endwise abutting relation to said fins, a head at the outlet end of the cylinder having a converging annular wall, said scoops extending along said wall and the latter being adapted to receive said nails and cleansing agent dumped from said scoops as the cylinder rotates and to reverse the direction of travel thereof whereby the forwardly falling mass from the scoops is caused to cascade over the rearwardly falling mass sliding down said converging wall to thus cause a vigorous scouring interaction to take place between the nails and the cleansing agent.

2. Apparatus for cleaning nails comprising a 25 rotary cylinder, helical fins on the interior surface thereof, scoops located in the cylinder in position to receive nails propelled forwardly by said fins, said scoops having inwardly extending flanges whereby they are effective to temporarily retain an appreciable bulk of nails delivered thereto by said fins, a substantially frusto-conical head secured to the outlet end of said cylinder and adapted to reverse the direction of travel of the nails dumped thereon whereby the forwardly falling mass discharged from the scoops is caused to cascade over the rearwardly falling mass sliding down the inner face of said frusto-conical head.

3. Apparatus for cleaning nails comprising a 30 rotary cleaning cylinder having helical fins therein, means for feeding a batch of nails and a cleansing agent into said cylinder, flanged scoops located in the cylinder in position for coaction with said fins, a head at the outlet end of the cylinder having a converging annular wall adapted to receive said nails and cleansing agent dumped from said scoops as the cylinder rotates, said scoops abutting the ends of said fins and extending along said converging annular wall, a cover controlling the discharge of said nails and cleaning agent from said cylinder, a slideable support for said cover adapted to be moved longitudinally toward and from said cylinder, a power operated device, and connections between said device and said support whereby opening or closing movements can be transmitted to said cover while the cylinder is rotating.

4. Apparatus for cleaning nails comprising a 35 screening drum, means for rotatably supporting the same, said drum having a plurality of spaced perforated sections, helical fins within the drum adapted to cause the nails and cleansing agent to move longitudinally of the drum as the latter

rotates, scoops in abutting relation to and receiving nails directly from said fins, a substantially frusto-conical head secured to the outlet end of the screening drum and encircling said scoops, a closure member normally blocking the outflow of nails from the screening drum, power actuated means for moving the closure member

5 to open position, a chute positioned to receive nails discharged from the screening drum and direct them to a suitable storage receptacle, and a member for receiving the cleaning agent discharged through the perforated sections of the drum.

WILLIAM THOMPSON.
